UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

SYSTEM OF FREQUENCY TRANSFORMATION.

1,316,995.

Specification of Letters Patent. Patented Sept. 23, 1919.

Application filed December 6, 1917. Serial No. 205,736.

To all whom it may concern:

Be it known that I, ERNST F. W. ALEXANDERSON, a citizen of the United States, residing at Schenectady, in the county of 5 Schenectady, State of New York, have invented certain new and useful Improvements in Systems of Frequency Transformation.

My present invention relates to the transformation of an alternating current of a 10 given frequency into an alternating current of a different frequency and to the utilization of the current thus transformed for radio signaling purposes.

Numerous systems have been heretofore 15 proposed for transforming an alternating current of fundamental frequency into an alternating current of a frequency harmonic to the fundamental frequency. In some of these systems means have been provided for 20 distorting the wave of the current of fundamental frequency from the sine wave form in such a way that certain harmonics are made prominent and these harmonics have been segregated in circuits which are resonant to the particular harmonic or harmonics which are to be utilized.

One of the objects of my invention is to 25 improve and simplify the operation of a system of the type mentioned. A further object of my invention is to provide a simple and efficient means for impressing an alternating current of harmonic frequency upon a radiating system for radio signaling purposes. A third object of my invention is to 35 provide a simple and efficient method for controlling the current in the radiating system in order to produce the desired signals therein.

In prior systems of the type in question, 40 it has usually been customary to tune the circuit of the fundamental frequency by means of a condenser in series with the source of supply and the iron core inductance which has been employed for distorting 45 the wave form. Such a circuit has a tendency to become unstable and in order to operate the same in a practical way it must be adjusted so that a substantially constant load is supplied from the source of energy 50 whether current is being supplied to the utilization system or not. A further object of my invention is to overcome this difficulty by providing a system which does not tend to become unstable and in which the energy 55 drawn from the source of supply will be a

minimum when no current of harmonic frequency is being supplied to the utilization system.

In carrying out this object of my invention I provide in shunt to the source of supply a capacity of such value as to compensate for the inductance of the circuit at no load. As a result when no energy is being withdrawn from the system the only current flowing therein will be a circulating current 60 between the capacity and inductance and the only energy required for maintaining this current will be that required to supply 65 the energy losses of the circuit.

The novel features which I believe to be 70 characteristic of my invention are set forth with particularity in the appended claims. The invention itself, however, both as to its organization and method of operation together with further objects and advantages 75 thereof will best be understood by reference to the following description taken in connection with the accompanying drawing in which I have illustrated diagrammatically one circuit organization whereby my 80 invention may be carried into effect.

As indicated in the drawing a source of energy, which in the present case is an alternating current generator 1, supplies current to the winding 2 of the iron core 3. A condenser 4 in series with the alternator 1 compensates for the internal inductance of the alternator. Condenser 5 in shunt to the alternator 1 is of such value as to compensate for the inductance of the winding 2. The 85 condenser 6 which is in series with the alternator is of such value as to compensate for the inductance 7 which is also in series with the alternator. With the system thus far described it will be apparent that the 90 capacity 5 will draw a leading current from the alternator and the inductance 2 will draw an equal lagging current so that when no current is supplied to the radiating system the actual energy which the alternator 95 is required to supply will be merely the energy required to make up the losses in the circuit. In utilizing this circuit arrangement for supplying current of harmonic frequency to a radiating system the terminal 100 8 of the alternator is grounded and the point 10 between inductances 7 and 9 is connected to the antenna 11. The effect of connecting the radiating system in this way is the same 105 as shunting the inductance 2 by a resistance 110

and hence the alternator 1 will be required to supply additional energy for maintaining current in the radiating system. For various reasons it is undesirable when current 5 of a harmonic frequency is supplied to the antenna that current of the fundamental frequency should also flow in the antenna. In order to prevent this the inductance 9 is arranged in inductive relation to the inductance 7 and so proportioned that the 10 point 12 at the end of this inductance is of substantially the same potential with respect to the fundamental frequency as the earth connection. In other words, there is a potential of fundamental frequency impressed 15 upon the harmonic frequency circuit which is equal and opposite to that impressed upon the inductance 2 from the source 1. This being the case there is no tendency for 20 current of the fundamental frequency to flow in the antenna. The antenna circuit is tuned by means of the usual variable inductance 13 to the harmonic frequency which it is desired to utilize. With the 25 arrangement here shown any desired odd harmonic of the fundamental frequency may be caused to flow in the antenna 11. If it were desired to utilize an even harmonic it would be necessary to employ a source of 30 direct current for saturating the core 3. The inductance 7 offers a high impedance to current of the harmonic frequency and hence but little current of harmonic frequency will flow in the fundamental frequency 35 circuit. The condenser 5 will offer a low impedance to current of the harmonic frequency and most of the harmonic frequency current which does flow through inductance 7 will pass through condenser 5 40 instead of flowing through the alternator.

In order to control the amplitude of the antenna current in order to produce signals a shunt circuit may be provided to the antenna and the impedance of this circuit 45 varied in accordance with the signals which are to be produced. In the present case I have illustrated a system whereby the antenna current may be varied to produce telephonic signals. The shunt circuit mentioned is connected to any suitable point 50 14 in the loading inductance 13 and comprises a magnetic amplifier or controller of the general type described in my United States Patent #1,206,643. In the present 55 instance the specific form of amplifier used consists of two iron cores 15 and 16 with windings 17 and 18 thereon, these two windings being connected in parallel with each other in the shunt circuit. Current for producing a normal saturation of the cores 15 60 and 16 may be derived from a direct current generator 19 which is connected in series with the windings 17 and 18, as indicated. A resistance 20 may be inserted in 65 this circuit in order to adjust the saturation

current desired for the most efficient operation. The condenser 21 is of such value as to offer a comparatively low impedance to the high frequency current but effectively prevents short circuiting of the 70 controlling current through the windings 17 and 18. A steady current from the generator 19 is also caused to flow through the multiple microphone 22. The field winding 23 of the alternator 1 is divided up into 75 four separate parts and the current which flows through the microphone 22 is led through these separate parts of the field winding 23 so that the field winding 23 acts as a steady inductance for the current 80 through the microphone. When the microphone 22 is acted upon by sound waves a variable potential is produced across its terminals and this variable potential is applied to the windings 17 and 18 in order to 85 vary the saturation in the cores 15 and 16 and thus vary the impedance of the shunt circuit. This variable potential is applied through the condensers 24, which condensers prevent the short circuiting the steady 90 microphone current. Condenser 25 in the shunt circuit is so adjusted that the circuit becomes resonant when the antenna current is a minimum.

This general method of modulating a high 95 frequency signaling current is described and claimed in my co-pending application, Serial No. 229,686, filed April 20, 1918, which is a continuation in part of my co-pending application, Serial No. 63,438, filed November 26, 1915.

While I have described my invention with particular reference to the transmission of telephonic signals, it will be apparent that it is by no means limited to this particular use but that it may be equally well employed for transmitting telegraphic signals if desired. It is also apparent that many modifications may be made in the circuit arrangement employed without departing 105 from the scope of my invention as set forth in the appended claims.

What I claim as new and desire to secure by Letters Patent of the United States, is:

1. Means for producing high frequency alternating currents comprising a source of alternating current of a fundamental frequency, and an electric circuit connected to said source, said circuit comprising an air core inductance and an iron core inductance, 115 series capacity in said circuit for neutralizing the inductance of the source and of the air core inductance and shunt capacity in said circuit for neutralizing the iron core inductance.

2. The combination in a radio signaling system of a source of alternating current of a fundamental frequency, an electric circuit connected to said source, said circuit comprising an air core inductance and an 120

- iron core inductance, series capacity in said circuit for neutralizing the inductance of the source and of the air core inductance, shunt capacity in said circuit for neutralizing 5 the iron core inductance and a radiating antenna system which is resonant to a frequency harmonic to the fundamental frequency associated with the iron core inductance.
- 10 3. The combination in a radio signaling system of a source of alternating current of a fundamental frequency, an electric circuit associated therewith which includes an iron core inductance, a radiating system which is resonant to a frequency harmonic to the fundamental and which also includes 15 said iron core inductance and means for impressing upon the radiating system a potential of the fundamental frequency which is equal and opposite to that impressed upon the iron core inductance from said source.
4. The combination in a radio signaling system of a source of alternating current of a fundamental frequency, an electric circuit connected to said source, said circuit comprising an air core inductance and an iron core inductance, series capacity in said circuit for neutralizing the inductance of the source and of the air core inductance, shunt 25 capacity in said circuit for neutralizing the iron core inductance, a radiating antenna system which is resonant to a frequency harmonic to the fundamental frequency associated with the iron core inductance, and means for impressing upon the radiating antenna system a potential of the fundamental frequency which is equal and opposite to that impressed upon the iron core inductance from said source.
- 30 5. The combination in a radio signaling system of a source of alternating current of a fundamental frequency, an electric circuit connected to said source, said circuit comprising an air core inductance and an iron core inductance, series capacity in said circuit for neutralizing the inductance of the source and of the air core inductance, shunt capacity in said circuit for neutralizing the iron core inductance, a radiating antenna system which is resonant to a frequency harmonic to the fundamental frequency associated with the iron core inductance, and a second air core inductance in the radiating antenna system which is so proportioned and related to the first air core inductance that it has impressed upon it a potential of fundamental frequency equal and opposite to that impressed upon the iron core inductance from said source.
- 45 6. The combination in a radio signaling system of an alternating current generator adapted to produce current of a fundamental frequency, a radiating antenna system, means for producing in said antenna system from said generator a current of a frequency 50 harmonic to the fundamental, a circuit in shunt to said antenna circuit containing a magnetic amplifier, a source of direct current, an inductance, a microphone, means for supplying current to said microphone from said direct current source through said inductance and means for supplying a variable current from said microphone to the windings of said amplifier.
7. The combination in a radio signaling system of an alternating current generator adapted to produce current of a fundamental frequency, a radiating antenna system, means for producing in said antenna system from said generator a current of a frequency 55 harmonic to the fundamental, a circuit in shunt to said antenna circuit containing a magnetic amplifier, a source of direct current, an inductance, a microphone, means for supplying current to said microphone from said direct current source through said inductance, means for supplying a variable current from said microphone to the windings of said amplifier, and means for supplying a constant current to the windings of 60 said amplifier from said direct current source.
8. Means for producing high frequency alternating currents comprising a source of alternating current of a fundamental frequency, an electric circuit connected to said source, said circuit comprising an iron core inductance and a shunt capacity for neutralizing the iron core inductance and a consumption circuit operatively related to 65 said iron core inductance and which is resonant to a frequency harmonic to the fundamental.
9. Means for producing high frequency alternating currents comprising a source of alternating current of a fundamental frequency, an electric circuit connected to said source, said circuit comprising an iron core inductance, a series capacity for neutralizing the internal inductance of the source and a shunt capacity for neutralizing the iron core inductance and a consumption circuit operatively related to 70 said iron core inductance and which is resonant to a frequency harmonic to the fundamental.
10. The combination in a radio signaling system of a source of alternating current of a fundamental frequency, an electric circuit connected to said source, said circuit comprising an iron core inductance and a radiating circuit which is resonant to a frequency harmonic to the fundamental frequency and which also includes said iron core inductance.
11. Means for producing high frequency alternating currents comprising a source of alternating current of a fundamental frequency and an electric circuit connected to said source, said circuit comprising an iron core inductance, a series capacity for neu- 75 80 85 90 95 100 105 110 115 120 125 130

- tralizing the internal inductance of the source and a shunt capacity for neutralizing the iron core inductance, a radiating system associated with said iron core inductance, and means for impressing upon said radiating system a potential of the fundamental frequency which is equal and opposite to that impressed upon the iron core inductance from the source.
10. 12. The combination in a radio signaling system of a source of alternating current of a fundamental frequency, an electric circuit connected to said source, said circuit comprising an iron core inductance, a series 15 capacity in said circuit for neutralizing part of the inductance of the circuit and a shunt capacity for neutralizing the iron core inductance and a radiating system which is resonant to a frequency harmonic to the 20 fundamental frequency and which also includes said iron core inductance.
13. The combination in a radio signaling system of a source of alternating current of a fundamental frequency, an electric circuit 25 connected to said source, said circuit comprising an iron core inductance, a series capacity in said circuit for neutralizing part of the inductance of the circuit and a shunt capacity for neutralizing the iron core inductance, a radiating system which is resonant to a frequency harmonic to the 30 fundamental frequency and which also in-
- cludes said iron core inductance, and means for impressing upon said radiating system a potential of the fundamental frequency 35 which is equal and opposite to that impressed upon the iron core inductance from the source.
14. Means for producing high frequency alternating currents comprising a source of 40 alternating current of a fundamental frequency, an electric circuit connected to said source, said circuit comprising an iron core inductance and an air core inductance and a series capacity for neutralizing the air 45 core inductance and a consumption circuit operatively related to said iron core inductance and which is resonant to a frequency harmonic to the fundamental.
15. Means for producing high frequency 50 alternating currents comprising a source of alternating current of a fundamental frequency, an electric circuit connected to said source, said circuit comprising an iron core inductance and an air core inductance, a 55 series capacity for neutralizing the air core inductance and a shunt capacity for neutralizing the iron core inductance and a consumption circuit operatively related to an iron core inductance which is resonant to a 60 frequency harmonic to the fundamental.

In witness whereof, I have hereunto set my hand this 4th day of December, 1917.

ERNST F. W. ALEXANDERSON.
